STORM DOOR

Sol Sofsky, N. Delsea Drive, Vineland, N.J.

Filed Nov. 27, 1964, Ser. No. 82,807

Term of patent 7 years

(Cl. D13—1)

FIGURE 1 is a perspective view of a storm door embodying my new design, showing the front face and the top and left hand edges thereof;

FIG. 2 is a front elevational view of the front face of the door;

FIG. 3 is a rear elevational view of the door; and

FIGS. 4, 5 and 6 are respectively cross sectional views taken on the lines 4—4, 5—5 and 6—6 of FIG. 2, in each case looking in the direction of the arrows.

I claim:

The ornamental design for a storm door, as shown.
